[57] CLAIM

The ornamental design for a flange for a bunged drum, as shown and described.

DESCRIPTION

FIG. 1 is a top perspective view of a flange for a bunged drum showing our new design;

FIG. 2 is a partial cross-sectional view thereof taken along line 2—2 of FIG. 1, broken away for ease of illustration;

FIG. 3 is a top view of the flange for a bunged drum in accordance with the invention;

FIG. 4 is a bottom view of the flange for a bunged drum in accordance with the invention; and,

FIG. 5 is a side elevational view of the flange for a bunged drum in accordance with the invention.
